UNITED STATES PATENT OFFICE.

ALEXANDER T. BROWN, OF SYRACUSE, NEW YORK.

TYPE-WRITING MACHINE.

No. 886,759.

Specification of Letters Patent.

Patented May 5, 1908.

Application filed November 10, 1905, Serial No. 286,708. Renewed December 14, 1907. Serial No. 406,486.

To all whom it may concern:

Be it known that I, ALEXANDER T. BROWN, citizen of the United States, and resident of Syracuse, in the county of Onondaga and State of New York, have invented certain new and useful Improvements in Type-Writing Machines, of which the following is a specification.

This invention relates to typewriting machines and more especially to the ribbon mechanism of such machines.

One of the objects of my invention is to provide an improved polychrome ribbon mechanism.

Another object is to provide an improved means for reversing the direction of feed of the ribbon, both automatically and by hand.

Another object is to provide improved means for turning the ribbon spools and for communicating motion from one ribbon spool shaft to the other.

A further object of my invention is to simplify and generally to improve the ribbon mechanism of a typewriting machine.

Other objects will appear hereinafter.

My invention is illustrated in the accompanying drawings in which,—

Figure 1 is a right hand side elevation, partly in section, of so much of a typewriting machine as is necessary to illustrate my invention. Fig. 2 is a top plan view of the same, the carriage being removed. Fig. 3 is a rear elevation of the same. Fig. 4 is a view of the same on a transverse vertical section taken about centrally of the type basket. Fig. 5 is a detail rear elevation of a device for transmitting the motion of one spool shaft to the other. Fig. 6 is an enlarged detail sectional view of a part of said device. Fig. 7 is a top plan view, partly in section, showing the ribbon feeding mechanism. Fig. 8 is a detail front view of a device for shifting the ribbon from one field to another. Fig. 9 is an enlarged detail sectional view of a stop device.

My invention is applicable to typewriting and similar machines generally and it is here shown applied to a Smith Premier typewriter. The main frame of this machine comprises side plates 1 connected together at their rear ends by a rear plate 2. Posts 3, rising from said side plates, support a top plate 4 which carries rails 5 having ball races formed therein. A platen 6 is mounted in a carriage 7 having grooved rails that are sup-

ported by anti-friction rollers 8 that co-operate with said grooved rails and with correspondingly grooved rails 5 mounted on the top plate 4. Printing keys 9 are mounted on key stems that move up and down in angled frame plates 10 that are mounted on the side plates 1 of the main frame and the lower ends of said key stems are pivoted to arms 11 projecting from rock shafts 12 (Fig. 1), the forward ends of which are pivoted in said frame plates 10 and the rear ends of which are pivoted in the back plate 2. Said rock shafts 12 are connected by links 13 with type bars 14 in such manner that when one of the keys 9 is depressed the corresponding type bar is operated to print on the under side of the platen 6.

Each of the rock shafts 12 has projecting therefrom near its rear end an arm 16 (Fig. 3) that is adapted to engage a gate or universal bar 17 mounted on arms 18 which are pivoted at 19 to said gate and at their opposite ends at 20 to the back plate 2. The universal bar or gate 17 is provided with a restoring spring 21. Said universal bar carries a bracket 22 which engages an arm 23 projecting from a vertical rock shaft 24 that is pivoted in the framework and has its upper end extending above the top plate 4. On the upper end of said shaft are mounted feed dogs 25 that co-operate with an escapement wheel 26 that is mounted on a shaft 26^a journaled in a housing 27 (Fig. 1). The shaft 26^a is geared through a pinion 28 to a feed rack 29 mounted on the rear rail of the carriage 7. The carriage is drawn across the machine by a tape 30 that winds on a pulley 31 integral with a drum 32, the hub of which, as shown in Fig. 7, is journaled on the reduced rear end of a sleeve 33, the forward end whereof is seated in a hole in the left hand rear post 3, or the right hand post as viewed in Fig. 7, which it will be noted is viewed as from the rear of the machine. The sleeve 33 is secured in position by a set screw 34 which is threaded through said post 3, and engages said sleeve. A carriage spring 35 is seated in a chambered-out portion of the drum 32, its outer end being connected to said drum. The inner end of said spring is connected to a lug 36 projecting from the hub 36^a of a toothed wheel 37 which may be turned to regulate the tension of the spring. The hub 36^a is journaled on the sleeve 33.

A ribbon spool shaft 38 is journaled at its

rear end in the sleeve 33 and its forward end in a suitable opening in the left-hand front post 3. Endwise motion of the shaft 38 towards the back of the machine is prevented 5 by a collar 39 mounted on said shaft and secured in position by a set screw 40. Said collar abuts the forward end of the sleeve 33. The shaft 38 extends beyond the rear end of said sleeve and has rigidly mounted thereon 10 the hub 41 of a ratchet wheel 42, said hub being secured in position by a pin 43 extending through said hub and the shaft 38. The hub 41 is recessed as shown in Fig. 7 to receive the hub of the drum 32. The ratchet 15 wheel 42 is engaged by a pawl 44 (Fig. 3) which is pivoted on a shouldered and headed screw 45 threaded into the drum 32. Said pawl is pressed into engagement with said ratchet wheel by a spring 46 connected at 20 one end to the tail of the pawl and at the other end to one of the spokes of the wheel 31. The construction is such that when the carriage is moving in printing direction toward the left the ratchet wheel 42 and the 25 shaft 38 will be turned by the pawl 44; but when said carriage is returned toward the right, said pawl may move idly over the teeth of the ratchet wheel without turning it or the shaft 38. A second ribbon spool shaft 47 is 30 journaled in suitable openings in the two right hand posts 3. Endwise motion of said shaft toward the front of the machine is prevented by a collar 48 (Fig. 7) secured to the shaft by a set screw 49 and contacting 35 with a washer 50 which abuts the rear side of the front post 3. Endwise motion of said shaft rearwardly is prevented by a screw 51 that is threaded into the end of the shaft and the head of which engages the post 3.

40 I have provided novel means for transmitting motion from the shaft 38 to the shaft 47. The shaft 47 projects some distance back of the rear post 3 and on its rear end there is mounted a crank arm 52, the hub of which is 45 secured to said shaft by a pin 53 extending through said hub and shaft. A rod 54 extends from the crank 52 to the ratchet wheel 42 and is connected to said crank and ratchet wheel by ball and socket joints of a 50 sort best shown in Figs. 5 and 6. Said rod 54 has enlarged spherical ends 55 that are received by hemispherical depressions in the rear faces of the ratchet wheel 42 and crank arm 52, respectively. Said spherical ends 55 are held against displacement by small plates 56 and 57, the former of which is secured by screws 58 to the rear face of the ratchet wheel 42. Said plate 56 is formed with an opening, shown in Fig. 6 at 59, of a 60 size to fit over the reduced neck of the rod 54 but not large enough to permit the passage of the ball or sphere 55. The plate 56 has an opening, the inner surface of which is of spherical form and enables said plate to fit 65 over the ball 55 and prevent it from escaping

from its socket. The plate 57 is secured to the arm 52 by a screw 60 and operates in the same way to retain the other ball 55 in place. The sockets in the ratchet wheel 42 and arm 52 are at the same distance from the centers 70 of the respective shafts 38 and 47. The rod 54 is bent in the form shown in Fig. 7 where it will be seen that said rod is straight throughout the greater part of its length but that its ends are bent toward the front of the machine, forming arms 54^a and 54^b, so that the straight part of the rod stands some distance back of a line joining the two balls 55. Said straight portion of the rod 54 is loosely mounted in open ended slots 61 (Fig. 1) 75 formed in two brackets 62 which depend from the top plate 4 to which they are secured by screws 63. The slots 61 are horizontal and extend in a front and back direction and the rod 54 is loosely mounted in said slots. The slots 61 are at substantially the same elevation as the shafts 38 and 47, and the rod 54 is free to turn in said slots and also to slide therethrough in any direction. 80

When the parts stand in the position shown in full lines in Fig. 5, the rod 54 acts as a rock shaft so that if the ratchet wheel 42 be turned, the forwardly bent end 54^b of the rod 54 that is connected with said ratchet wheel will be depressed, thus rocking the rod 54 in its 95 bearings and depressing the forwardly bent arm 54^a of said rod that is connected to the crank 52 so that said crank will also be depressed. When the parts reach the position shown in dotted lines in Fig. 5, the rod 54 100 acts as a link and if then the ratchet wheel 42 be turned, said rod will move towards the right of the operator, that is to say, toward the left as shown in Fig. 5, and will turn the crank 52 in the same direction. In positions 105 intermediate the dotted line and full line positions of Fig. 5 the cranking action and link action of the connection 54 will be combined. It will be observed that in the full line position of Fig. 5 the rod 54, considered as a link, 110 is on the dead center; but considered as rock shaft having two forwardly extending arms, it is at its best position for work. In the dotted line position of Fig. 5 the rod 54, considered as a rock shaft, is on the dead center; but considered as a link it is in its best position for transmitting motion. It will thus 115 be seen that this rod transmits motion by a sort of combined crank shaft and link action, in some positions one of these actions taking 120 place alone and in other positions the two actions taking place simultaneously. The result is that motion is transmitted equally well in all positions, the parts having no dead center in any position. It will also be understood that in addition to sliding longitudinally, the rod 54 slides from front to back of the machine in the slots 61. In the full line position of Fig. 5 the rod will stand in its rear- 125 most position and in the dotted line position 130

of Fig. 5 it will stand slightly forward of said rearmost position due to the inclination of the forwardly bent arms of the rod. It will, of course, be understood that the operation 5 of the rod would be the same if it were straight throughout its entire length and had arms at its ends projecting at right angles toward the front of the machine; but I have preferred to extend said arms at the angle shown, it being 10 merely necessary to so shape the arms that they do not interfere with other parts of the mechanism, such, for instance, as the hub 41 and the rear end of the shaft 43. This connection is an extremely simple and convenient 15 means for communicating motion from one of two parallel shafts to the other. It will be obvious that the motion of the two shafts will be in the same direction. In order to positively prevent rotation of the shafts 38 20 and 47 in a right hand direction, a ratchet wheel 64 (Fig. 3) is rigidly mounted on the shaft 47 and is engaged by a weighted pawl 65 that is pivoted on a shouldered and headed screw 66 threaded into the post 3.

25 As best appears in Fig. 7, a ribbon spool 67 is loosely mounted on the shaft 38 just back of the forward post 3 and consists of a hollow sheet metal core supported by two end flanges 68 which are journaled on said shaft. Endwise motion of said spool toward the front of the machine is prevented by a washer 69 interposed between one of the flanges 68 and the forward post 3; and endwise motion of said spool in the other direction is prevented 30 by a pin or screw 70 projecting from the shaft 37 just within said flange 68. A similar spool 71 is loosely mounted on a shaft 47 just in front of the rear post 3. Motion of said spool toward the back of the machine is prevented 35 by said post and motion of said spool toward the front of the machine is prevented by a pin or screw 72 projecting from the shaft 47 just in front of the rear flange 68 of the spool.

40 It will be observed that the rear end of the spool 67 is somewhat nearer the front of the machine than the front end of the spool 71; and the ribbon is led from one of these spools to the other in an off-set path as shown in Fig. 2 by means of certain guides which will 45 now be described. The ribbon 73 is guided upward from the spools through suitable slots in the top plate and is guided over two plates 74 that are secured to the top plate by screws 75 (Fig. 2). A movable guide plate 50 76 has an elongated opening 77 through which the type are adapted to strike against the ribbon as shown in said Fig. 2. Said guide plate also has two openings 78 and 79, the latter being behind the former. The ribbon 55 passes from the spool 67 over the left-hand plate 74, under the guide plate 76, up through the oblique guide opening 74, thence toward the rear of the machine over the type opening 77, down through the oblique opening 79, thence under the plate 76 and over

the right hand plate 74, and thence downward through the right hand slot to the spool 71. The rear edge 80 of the opening 78 and the forward edge 81 of the opening 79 are parallel and preferably at angles of 45° with the direction of the travel of the carriage so that the part of the ribbon that lies over the printing point extends from front to back of the machine. It will be seen from Fig. 2 70 that the printing point is a little back of the left-hand ribbon spool and a little in front of the right hand spool so that the type strike only the fore and aft extending part of the ribbon.

75 The guide plate 76 is mounted to slide in a direction parallel to that of the motion of the carriage. A frame bar 82 is mounted on the top plate 4 and lies partly under the forward carriage rail 5 but out of contact with said rail. The bar 82 has a longitudinal slot 83 therein and two ears 84 are bent downward from the forward edge of the plate 76 into said slot 83 and serve to guide the plate. The rear end of the plate 76 passes under a frame bar 85 and is bent up behind said bar 90 and forward over the edge of said bar, forming a flange or rib 87 that lies over the top of the bar 85. An arm 88 projects toward the front of the machine from the plate 76, said arm lying over the bar 82 and under the carriage rail 5. The arm 88 has its forward end formed into a pointer or index 89 and said arm carries a finger piece 90 by which the plate 76 may be slid to the right or left, as will be understood. As best shown in Figs. 100 2 and 8, the arm 88 near its forward end passes under a transversely extending bar 91 that has at its ends two short posts 92 and which is secured to the top plate by screws 93. The bar 91 is toothed on its under side 105 and the arm 88 where it lies beneath said bar is formed with a tooth 94 which is adapted to coöperate with the teeth on the bar 91 to hold the plate 76 in any position to which it may be set. The arm 88 is resilient and 110 presses the tooth 94 up against the bar 91. When it is desired to move the plate 76 the finger piece 90 is depressed to move the tooth 94 away from the bar 91, after which said finger piece is moved to the right or left as 115 desired, its motion being limited by the posts 92. The construction is such that if the arm 88 stands against the right hand post 92, the forward edge of the ribbon will be fed over the printing point. In whatever position 120 the arm 88 stands the longitudinal feed of the ribbon will result in a single longitudinal line of the ribbon being fed under the printing point.

125 It will be obvious that this device is capable of use with a ribbon of uniform character throughout and that the entire surface of the ribbon may be utilized by the operator taking care occasionally to change the adjustment of the arm 88. This mechanism is, 130

however, especially adapted for use with a ribbon having two or more longitudinal fields of different characteristics, such, for example, as a ribbon that is inked in longitudinal stripes with different colors or different kinds of ink and which is commonly called a poly-chrome ribbon. One of the stripes, for example, may be red, another blue and another black, or there may be one stripe of record ribbon and one stripe of copying ribbon. In the present instance I have shown a ribbon having three stripes of different characteristics. In order that the operator may readily adjust the parts to use one or the other of these fields, I have mounted beneath the index 89 an indicator 95, said indicator being of a width corresponding to the width of the ribbon and marked with colors or other indicating devices corresponding to the different stripes of the ribbon used in the machine. It will be obvious that any other suitable form of indicator may be used. In the present instance the indicator is a separate piece of material secured in position by a frame 25 consisting of a plate 96, the rear edge of which rests beneath the posts 92 and the forward edge of which is secured to the top plate by screws 97. It will be obvious that the indicator 95 may very well consist of a short section cut from the ink ribbon that is in use in the machine.

It is sometimes desirable to remove or shift the ribbon entirely from the printing point. In some machines this is done to inspect or 35 clean the type and in the Smith Premier machine this is done for the purpose of inserting a crank to operate a type cleaning brush that is permanently mounted in the machine. It may also be desirable to shift the ink ribbon 40 to uncover the printing point in case the machine is used for doing mimeograph work. In the present instance this is readily provided for by making the bar 91 of such a length as to admit of a motion of the arm 88 of sufficient extent to carry the plate 76 entirely away from the printing point. This extreme position of the parts is indicated in dotted lines in Fig. 2.

It is sometimes convenient to have an adjustable stop to limit the motion of the arm 88 and I have shown such a stop in the present instance. A piece of sheet metal 98 (Fig. 9) is bent about the bar 91, extending underneath and up behind said bar. Said sheet metal piece also extends up in front of the bar to a point a short distance above said bar, whence it is bent backward forming a finger piece 99. A flat spring 100 is bent into a U-shape and is sprung over the bar 91 and under the sheet metal piece 98, the tension of the spring tending to press upward on said sheet metal piece. A tooth 101 is stamped up from the sheet metal piece 98 and is adapted to be pressed by the spring 100 into one of the notches on the under side

of the bar 91. When it is desired to change the adjustment of the stop, the operator presses with his finger on the finger piece 99, thus depressing the tooth 101 away from the bar 91, after which the stop may be slid along 70 said bar in either direction. The spring plate 100 is retained in position by having the edges of a hole therein bent upward into a corresponding hole in the piece 98, as shown at 102. The piece 98 has a stop lug 103 bent 75 down therefrom in position to engage the arm 88 of the ribbon guide.

I have provided means for coupling one or the other of the ribbon spools 67 and 71 to its shaft in order to feed the ribbon longitudinally in one direction or the other. The ribbon spool 67 is formed on its rear end with clutch teeth 104 (Fig. 7) which are adapted to be engaged by clutch teeth 105 formed on the forward end of a sleeve 106 that is slidably mounted on the shaft 38 but is prevented from rotation relatively to said shaft by a pin 107 that passes through said shaft and extends into a longitudinal slot in the sleeve 106. Said sleeve is formed with a worm 108. The ribbon spool 71 has clutch teeth 109 formed on the forward end thereof and said clutch teeth are adapted to co-operate with clutch teeth on the rear end of a sleeve 110 that is slidably mounted on the 95 shaft 47 but is constrained to turn in unison with said shaft by a pin 111 passing through the shaft and extending into a longitudinal slot in the sleeve. The sleeve 110 is formed with a worm 112. The sleeve 106 is formed with an annular groove that is engaged by a forked or notched arm 113 (Fig. 4) bent off from an upright arm 114 that is mounted at its lower end on a shaft 115 by means of a set screw 116 threaded through the hub of said arm and engaging said shaft. The shaft 115 extends across the machine beneath the series of rock shafts 12 and is pivoted at its ends on pivot screws 117 threaded through the side plates 1 and having reduced ends 110 entering suitable openings in the ends of the shaft 115. On the right hand end of said shaft 115 a second upright arm 118 is mounted, being secured in position by a set screw 119 threaded through the hub of the arm and 115 engaging the shaft. Said arm 118 has bent off therefrom a forked or notched arm 120 that engages an annular groove in the sleeve 110. The construction is such that if the shaft 115 be rocked toward the rear of the 120 machine the sleeve 110 will be clutched to the spool 71, thus causing said spool to turn with the shaft 47, whereas the sleeve 106 will have its clutch teeth 105 out of engagement with the clutch teeth 104 on the spool 67 so that 125 this latter spool will be uncoupled from its shaft. If by any means the shaft 115 and the arms 114 and 118 be turned toward the front of the machine, both sleeves will move toward the front of the machine, thus coup- 130

ling the spool 67 to its shaft and uncoupling the spool 71 from its shaft. In order to hold this shifting mechanism in one or the other of its shifted positions the following means are provided. One of the upright arms, in the present instance, the arm 118 is extended above its off-set arm 120 as best shown in Figs. 1 and 4. At the upper end of the arm 118 a double link 121 is pivoted to said arm by a pin 122. The upper ends of the two plates constituting said double link and connected by a pin 123 on which is pivoted the rear end of a flat spring 124, the forward end of which rests on the top of one of the posts 15 3 to which it is secured by a screw 125. The tension of the spring 124 is exerted downward and the parts are so proportioned that when the arm 118 is in its rear position the link 121 is inclined downward and toward the rear of the machine so that the tension of the spring tends to press said arm toward the rear of the machine. When the parts are shifted and the arm 118 moved toward the front of the machine the link 12 passes its 20 dead center and moves to a position where it is inclined downwardly toward the front of the machine so that the tension of the spring 124 is now exerted to hold the parts in their forward positions. It will be apparent, however, that the parts may be shifted at any 25 time by the application of a slight force and that this may be done by hand, the operator taking hold of one of the arms 114, 118. I have, however, provided automatic means 30 for effecting the shift, the worms 108 and 112 being parts of said means.

As best shown in Figs. 1 and 4, a short rock shaft 126 is loosely mounted in ears 127 depending from a plate 128 that is secured 40 to the under side of the top plate 4 by screws 129. The rock shaft 126 is situated above and a little to the right of the axis of the spool 71 and said rock shaft has a plate-like arm or wing 130 extending therefrom and 45 said arm, or fingers 131 thereof, rests by gravity on the ribbon wound on said spool 71.

As best shown in Fig. 7, the core of the spool 71 has slots 132 formed therein into which, when that part of the spool is entirely 50 uncovered, the fingers 131 may drop. The forward end of the shaft 126 has bent off therefrom an arm 133, the free end of which constitutes a tooth or tripper. The construction is such that when the ribbon is 55 nearly exhausted from the spool and uncovers the slots 132, the fingers 131 drop into the slots and the free end of the arm 133 drops into engagement with the worm 112, which worm rotates with the shaft 47. The 60 continued rotation of said shaft and worm causes the worm to be forced lengthwise of the shaft 47 toward the rear of the machine until the link 121 has passed its dead center and the clutch teeth connected with said 65 worm engage the clutch teeth 109 on the

spool 71, thus coupling said spool to the shaft. As has been explained above, this uncouples the other spool from its shaft. Above and to the right of the spool 67 there is mounted a rock shaft 135 similar to the 70 rock shaft 126. Said shaft 135 is journaled at its ends in ears 136 depending from a plate 137 which is secured by screws 138 to the under side of a part of the top plate 4. The shaft 135 has projecting therefrom a 75 wing or arm 139 (Fig. 4) having fingers 140 (Fig. 1) that normally rest on the ribbon but that are adapted to drop when the ribbon is nearly exhausted into slots 141 (Fig. 7) in the spool 67. The shaft 135 has an arm 80 similar to the arm 133, the end of which is adapted to drop into engagement with the worm 108 and to cause said worm to move itself towards the front of the machine and thus couple the spool 67 to its shaft and 85 uncouple the spool 71 from its shaft, thus reversing the direction of the feed of the ribbon.

Either of the ribbon spool shafts 38 and 47 may have mounted on its forward end a hand crank 142 by which the ribbon may be fed 90 longitudinally by hand.

Various changes may be made in the arrangement and construction of the devices above described without departing from the spirit of my invention.

What I claim as new and desire to secure by Letters Patent, is:—

1. In a typewriting machine and in a ribbon mechanism, the combination of two ribbon spools; two parallel shafts, one for each of 100 said spools; means for driving said shafts, each of said shafts being always turned in the same direction; and means for connecting either of said spools to turn with its shaft and for disconnecting the other of said spools. 105

2. In a typewriting machine and in a ribbon mechanism, the combination of a pair of ribbon spools, shafts on which said ribbon spools are mounted, a spring drum surrounding one of said shafts and having a driving 110 connection with both of said shafts, a carriage driven by said spring drum, and means for coupling either of said spools to turn with its shaft and uncoupling the other spool.

3. In a typewriting machine and in a ribbon mechanism, the combination of a pair of ribbon spools, a shaft for each of said spools, a spring drum surrounding one of said shafts and having pawl and ratchet connection therewith, a driving connection from said 120 shaft to the other of said shafts, and means for coupling either of said spools to its shaft and uncoupling the other spool.

4. In a typewriting machine and in a ribbon mechanism, the combination of two 125 shafts, means for turning said shafts in unison, a ribbon spool mounted on each of said shafts, a clutch member slidably mounted on each of said shafts, a clutch member on each of said ribbon spools, and means for 130

- sliding one of said slideable clutch members into engagement with its mate, and the other of said slideable clutch members out of engagement **with its mate** to reverse the direction of feed of the ribbon.
5. In a typewriting machine and in a ribbon mechanism, the combination of a pair of rotary shafts, a ribbon spool mounted on each of said shafts, each of said ribbon spools being provided with a clutch member, a worm mounted on each of said shafts and provided with a clutch member, and ribbon controlled trip devices for engaging said worms to effect a reverse in the direction of feed of the ribbon.
10. 6. In a typewriting machine and in a ribbon mechanism, the combination of two rotary shafts, a ribbon spool mounted on each of said shafts, each of said ribbon spools having a clutch member, a coöperating clutch member slidably mounted on each of said shafts and movable into and out of engagement with the clutch member on the ribbon spool, and a connection between said slideable clutch members for causing one of said 20 clutch members to move out of engagement with its ribbon spool when the other of said clutch members moves into engagement with its ribbon spool.
15. 7. In a typewriting machine and in a ribbon mechanism, the combination of a pair of rotary shafts, a ribbon spool mounted on each of said shafts, each of said ribbon spools having a clutch member, a worm slidably mounted on each of said shafts, each of said 25 worms having a clutch member, ribbon controlled trip devices for engaging said worms, and connections whereby when one of said worms is moved to bring its clutch member into engagement with its mate the other of 30 said clutch members is moved out of engagement with its mate.
8. In a typewriting machine and in a ribbon mechanism, the combination of two parallel rotary shafts, a member slidably mounted on each of said shafts, said members being provided with clutch teeth on one end thereof, the clutch teeth on one member being on the opposite end from the clutch teeth on the other member, means for sliding said 35 members in the same direction, and a pair of ribbon spools having clutch members coöperating with the clutch teeth on said sliding members, whereby when said sliding members are moved in one direction one of said 40 ribbon spools will be coupled to its shaft and the other will be uncoupled to feed the ribbon in one direction, and when said members are moved in the other direction the feed of the ribbon will be reversed.
45. 9. In a typewriting machine and in a ribbon mechanism, the combination of two members mounted to rotate on parallel axes, and a driving connection between said members comprising a combined link and crank- 50 ing member connected eccentrically with each of said rotary members by a universal joint.
10. In a typewriting machine, the combination of two members mounted for rotation about parallel axes, and means for communicating rotary motion from one of said members to the other, said means comprising a member mounted to rock about an axis at right angles to said parallel axes and to move in the direction of its length, said member being eccentrically connected with each of said rotary members by a universal joint.
11. In a typewriting machine and in a ribbon mechanism, the combination of two parallel shafts, a ribbon spool mounted on each 55 of said shafts, a clutch member on one end of one of said ribbon spools, a clutch member on the opposite end of the other of said ribbon spools, coöperating clutch members slidably mounted on said shafts, and a rocking member operatively connected with each of said clutch members to constrain them to slide in the same direction, whereby when one of said clutch members is moved into engagement the other will be moved out of engagement, 60 and means for rotating said shafts.
12. In a typewriting machine and in a ribbon mechanism, the combination of two shafts on opposite sides of the machine, a ribbon spool mounted on each of said shafts, 65 one of said ribbon spools having a clutch member on one end thereof and the other of said ribbon spools having a clutch member on the opposite end thereof, coöperating clutch members slidably mounted on said 70 shafts, and a rock shaft extending across the machine and having arms for controlling the sliding motion of said slideable clutch members.
13. In a typewriting machine and in a ribbon mechanism, the combination of two rotary shafts mounted on opposite sides of the machine, a ribbon spool mounted on one of said shafts forward of the printing point and having a clutch member on its rear end, a 75 ribbon spool mounted on the other of said shafts back of the printing point and having a clutch member on its forward end, coöperating clutch members slidably mounted on said shafts, means for causing said clutch 80 members to slide in the same direction, and means for guiding an ink ribbon from one of said spools to the other in an off-set path.
14. In a typewriting machine, the combination of two shafts, and a connecting member for causing said shafts to turn in unison, said connecting member being mounted for oscillatory and sliding motion and having arms eccentrically connected with said shafts by universal joints.
15. In a typewriting machine, the combination of two shafts located at a distance apart, and a connecting member for causing said shafts to rotate in unison, said connecting member being mounted for longitudinal 85 motion.

and oscillatory motion and having two arms each eccentrically connected with one of said shafts by a universal joint.

16. In a typewriting machine, the combination of two rotary shafts located at a distance apart, and a connecting member for causing said shafts to rotate in unison, said connecting member consisting of a rod having two arms one eccentrically connected 10 with each of said rotary shafts by a universal joint, said rod at one part of the rotation of said shafts acting as a link and at another part of the rotation of said shafts acting as a crank shaft.

15 17. In a typewriting machine and in a ribbon mechanism, the combination of two parallel ribbon spool shafts, ribbon spools mounted on said shafts, means for driving one of 20 said shafts, and means for communicating the motion of said driven shaft to the other of said shafts, said means comprising a member mounted for longitudinal and rocking motion and having two arms, one eccentrically connected with each of said shafts by a 25 universal joint.

18. In a typewriting machine and in a ribbon mechanism, the combination of two shafts, means for turning both of said shafts, a pair of ribbon spools one mounted on each 30 of said shafts, and means for coupling either of said spools to its shaft and uncoupling the other spool.

19. In a typewriting machine and in a ribbon mechanism, the combination of two ribbon spools at opposite sides of the machine, a ribbon guide between said spools having 35 two oblique guide surfaces so disposed that the part of the ribbon between said oblique surfaces is opposite the printing point, a ribbon having longitudinal fields of different 40 characteristics, hand operated means for moving said movable guide to bring one or another of said fields to the printing point without affecting said ribbon spools, and an indicating device to indicate which field of 45 the ribbon is at the printing point.

20. In a typewriting machine and in a ribbon mechanism, the combination of two ribbon spools at opposite sides of the machine, 50 an ink ribbon having longitudinal fields of different characteristics, a ribbon guide having oblique surfaces for guiding said ribbon across the printing point in an off-set path, the printing point being between said oblique surfaces, means for moving said guide in the general direction of the longitudinal feed of the ribbon, whereby any desired one 55 of said longitudinal fields may be brought to the printing point, an indicating device for indicating which of said fields is at the printing point, and means for retaining said guide in different set positions.

21. In a typewriting machine and in a ribbon mechanism, the combination of two rib-

bon spools at opposite sides of the machine, 65 an ink ribbon having longitudinal fields of different characteristics, a guide for said ink ribbon having oblique guide surfaces for guiding said ribbon across the printing point in an off-set path, the printing point being between said oblique surfaces, hand operated means extending to the front of the machine for moving said guide to different set positions to bring one or another of said fields to the printing point, an indicating device to 70 show which of said fields is at the printing point, and means for retaining said guide in different set positions.

22. In a typewriting machine and in a ribbon mechanism, the combination of two ribbon spools at opposite sides of the machine, 80 an ink ribbon having longitudinal fields of different characteristics, a guide for said ink ribbon having oblique guide surfaces for guiding said ribbon across the printing point in 85 an off-set path, the printing point being between said oblique surfaces, hand operated means extending to the front of the machine for moving said guide to different set positions to bring one or another of said fields to 90 the printing point, an indicating device to show which of said fields is at the printing point, and means comprising a toothed bar for retaining said guide in different set positions.

95 23. In a typewriting machine and in a ribbon mechanism, the combination of two ribbon spools at opposite sides of the machine, 100 an ink ribbon having longitudinal fields of different characteristics, a guide for said ink ribbon having oblique guide surfaces for guiding said ribbon across the printing point in 105 an off-set path, the printing point being between said oblique surfaces, hand operated means extending to the front of the machine for moving said guide to different set positions to bring one or another of said fields to the printing point, an indicating device to show which of said fields is at the printing point, means comprising a toothed bar for 110 retaining said guide in different set positions, and a stop adjustably mounted on said bar.

24. In a typewriting machine and in a ribbon mechanism, the combination of a ribbon spool having a clutch device on one end 115 thereof; a worm mounted co-axially with said ribbon spool and having a co-operating clutch device; means for rotating said worm; and a pivoted tripping device having an arm adapted to rest on the ribbon and another 120 arm adapted to engage said worm when the ribbon is nearly exhausted from the spool.

25. In a typewriting machine and in a ribbon mechanism, the combination of a shaft; means for rotating said shaft; a ribbon spool loosely mounted on said shaft and having a clutch device on one end thereof; 125 a worm slidably mounted on said shaft and

- having a coöperating clutch device; and a pivoted tripping device having two arms, one adapted to rest on the ribbon and the other adapted to engage said worm when the ribbon is nearly exhausted from the spool. 45
26. In a typewriting machine and in a ribbon mechanism, the combination of two ribbon spools each having a clutch member; two worms, one mounted co-axially with each of said spools and each having a co- 50 operating clutch member; a pivoted tripping member for each of said spools, each of said tripping members having one arm adapted to rest on the ribbon and another arm adapted to engage said worm when the ribbon is 55 nearly exhausted from the spool; and a connecting device for causing one of said worms to be uncoupled from its spool when the other of said worms is coupled to its spool. 60
27. In a typewriting machine, the combination of two spool shafts; ribbon spools thereon; and a link connecting one shaft with the other shaft and adapted to transmit motion from one shaft to the other by longitudinal and rotary motion of said link. 65
28. In a typewriting machine, the combination of two spool shafts, ribbon spools thereon; means for driving one of said shafts; two parts, one fixed to each shaft and rotating therewith; and a link having its ends directly connected to said parts and adapted to transmit motion from the driving shaft to the driven shaft whenever said driving shaft is turned by said driving means. 70
29. In a typewriting machine and in ribbon mechanism, the combination of two ribbon spools; two parallel shafts, one for each of said spools; a clutch device for each spool and shaft, each of said clutch devices 75 comprising a member constrained to turn with the shaft and a member constrained to turn with the ribbon spool; and means for throwing one pair of clutch members into engagement and the other pair out of engagement. 80
30. In a typewriting machine and in ribbon mechanism, the combination of two ribbon spools; two shafts, one for each of said spools; a pair of coöperating clutch members for each spool and shaft, one member of each clutch being movable longitudinally of the shaft into and out of engagement with the other member and the construction and arrangement being such that when said movable clutch members are moved in the same direction, one of the clutches will be coupled and the other uncoupled; and means for moving said movable clutch members in the same direction. 85
31. In a typewriting machine, the combination with two parallel shafts, of means for causing said shafts to turn in unison, comprising a connecting rod which in one position of the parts acts as a link connecting said shafts and in another position of the parts acts as a crank shaft. 90
32. Means for driving one rotary device from another, consisting of a connecting device or link connected eccentrically with each of said rotary devices and having a rocking motion about an axis extending longitudinally of said link. 95
33. The combination of two rotary members and a connecting link for driving one of said rotary members from the other, by longitudinal reciprocation of said link and by oscillation of said link about an axis extending longitudinally of said link. 100
